United States Patent Office

Des. 216,288
Patented Dec. 9, 1969

216,288

INVALID WALKER

Charles E. Murcott, Valley Drive, Bay Crest,
Huntington, N.Y. 11743

Filed Mar. 21, 1969, Ser. No. 16,366

Term of patent 14 years

Int. Cl. D24—04

U.S. Cl. D88—5

Fig. 4

Fig. 3

Fig. 1

Fig. 2

FIG. 1 is a perspective view of an invalid walker showing my new design;

FIG. 2 is a right side elevational view thereof;

FIG. 3 is a front elevational view thereof; and

FIG. 4 is a top plan view thereof.

The side opposite that shown is substantially the same as the side that is shown.

I claim:

The ornamental design for an invalid walker, substantially as shown and described.
